BRUNO H. THEISEN AND GEORGE S. KELLER, OF MINNEAPOLIS, MINNESOTA.

PRESSER-FOOT MECHANISM FOR STITCHING-MACHINES.

973,237.

Specification of Letters Patent. Patented Oct. 18, 1910.

Application filed May 13, 1909. Serial No. 495,741.

To all whom it may concern:

Be it known that we, BRUNO H. THEISEN and GEORGE S. KELLER, both of Minneapolis, Hennepin county, Minnesota, have invented 5 certain new and useful Improvements in Presser-Foot Mechanisms for Stitching-Machines, of which the following is a specification.

The object of our invention is to provide 10 means for holding the material to be stitched securely on the work plate during the operation of punching the hole therein and forming the stitch.

A further object is to provide means, 15 which will adjust themselves automatically to the varying thicknesses of the material that is to be worked on.

Our invention consists generally in various 20 constructions and combinations, all as hereinafter described and particularly pointed out in the claims.

In the accompanying drawings, forming 25 part of this specification, Figure 1 is a front view of a stitching machine, embodying our invention, Fig. 2 is a side view partially in section, of the same, Fig. 3 is an enlarged, detail view, illustrating the presser foot mechanism.

In the drawing, 2 represents a work support 30 and 3 a presser foot mounted on a lever 4 that is loosely supported on the shaft 5 and capable of vertical oscillation independently thereof. The end of the presser foot is directly above the work support, in 35 position to engage and hold the material securely thereon. The lever 4 is provided with a laterally turned end 6, which projects over an arm 7 that is loosely mounted on a shaft 8 between the standards 9 of the machine 40 and said arm has a curved rack bar 10 at one end in position to engage a tooth 11 on a trip lever 12, that is pivoted at its lower end between the standards and has a hand grip 13 and is normally pressed toward the rack 45 bar 10 by a spring 14. The arm 7 by engaging the laterally turned end 6, tends to raise that end of the lever and depress the presser foot. A spring 15 normally holds the arm 7 in yielding engagement with the 50 end 6. A secondary lever 16 is mounted on the shaft 8 and has an end adapted to engage the under side of the lever 4 and is held in contact therewith by a spring 17. This spring has considerable tension and the 55 lever 16 is held firmly thereby against the lever 4 and the presser foot locked securely

in engagement with the material to be stitched. The lever 16 has a lug 18 projecting therefrom on one side into the path of the oscillating needle jaw 19, which is actuated from the crank shaft 20 through a connecting rod 21. When the jaw has descended to a predetermined position, it will engage the lug 18 and tilt the lever 16 to the position shown in Fig. 2, relieving the pressure on the lever 4 and allowing the presser foot to be released when the lever 12 is disengaged from the rack bar 10. To automatically operate this lever 12, we prefer to provide a lug 22 on the upright rocking post 23, which is actuated through the engagement of the depending bracket 24 with the cam 25 on the shaft 20 and supports an arm 26 through the operation of which, the awl carrying jaw 27 is oscillated to feed the goods. An adjusting screw 28 is mounted in the lug 22 in position to engage the edge of the lever 12 and at a predetermined point in the operation of the machine, disengage the said lever from the rack bar 10 and allow the arm 7 to swing downward and release the presser foot. A spring 29 normally presses the arm 26 away from the awl jaw and holds the screw 28 out of the path of the lever 12. The operation of the mechanism is so timed that the oscillation of the post 23, the movement of the arm 26 and the lateral stroke of the jaw 27 through its engagement with said arm will take place just at the time when the awl is completing its upward movement, 90 so that the oscillation of the jaw 27 will move the awl laterally in the work plate and feed the material forward. This awl feed however, forms the subject matter of a separate application and is not claimed herein. 95

The mechanism last described in connection with the presser foot, will, as indicated in Fig. 2, be actuated also to release the presser foot, just at the time it is desired to make the feed. 100

The ratchet device in connection with the arm 7 and the lever 4 allows the presser foot to adjust itself to different thicknesses of material. For instance, if the lever 12 be adjusted for a certain thickness of material 105 and during the operation of the machine, a thinner portion of the material is fed along to be stitched, the ratchet bar will slide upwardly on the tooth 11 actuated by its spring and tilt the lever 4 and force the presser foot downwardly to keep it constantly in engagement with the surface of the material. 110

If the material grows thicker as the feed progresses, the operator may grasp the handle 13, disengage the lever from the ratchet bar and allow the presser foot to adjust itself to the variation. Generally however, the lever 12 will be automatically tripped just before the feeding operation to allow the presser foot to accommodate itself to the thickness of the material.

10 We claim as our invention:—

1. In a stitching machine, the combination, with a work support, a needle jaw and an awl jaw, of a pivoted lever, a presser foot mounted thereon, a spring pressed arm arranged to engage said lever and having a series of ratchet teeth, a trip lever having a tooth to engage said ratchet teeth and normally locking said arm in engagement with said lever, means for operating said awl jaw 15 to feed the goods and adjustable means carried by said operating means and arranged to engage said trip lever and release said arm, substantially as described.

2. In a stitching machine, the combination, with a work support, a needle jaw and an awl jaw, of a pivoted lever, a presser foot mounted thereon, said lever having a laterally extending end, a pivoted spring-pressed arm having a U-shaped recess to receive and 20 loosely support said laterally extending end and hold said presser foot toward said work support with a yielding pressure, said arm having a series of ratchet teeth thereon, and a trip lever having a tooth to engage said 25 teeth, said arm slipping automatically over said tooth to increase the pressure of said foot on said plate but being normally locked by said tooth against movement in the other direction.

3. The combination, with a work support, a needle jaw and an awl jaw, of a presser foot lever, a presser foot carried thereby, a spring-pressed arm having a series of teeth, and a part to engage said presser foot lever, 30 a trip lever having a tooth to engage said ratchet teeth and normally lock said arm in engagement with said presser foot lever, said arm slipping automatically over the tooth of said trip lever and permitting the presser 35 foot to accommodate itself to the varying thickness of the material, and means actuated by said needle jaw for releasing the pressure of said presser foot lever at a predetermined point, substantially as described.

4. In a stitching machine, the combination, with a reciprocating needle jaw and an awl jaw, and means for operating the same, of a work support, a presser foot lever, a presser foot mounted thereon, a spring- 40 pressed ratchet arm arranged to engage said presser foot lever and having a series of ratchet teeth, a spring-pressed tripping lever having a tooth to engage the teeth of said ratchet arm, a spring-pressed lever arranged to engage said presser foot lever and

having a lug projecting into the path of said needle jaw, and a feed mechanism arranged to advance the material and actuate said tripping lever to disengage it from the teeth of said ratchet arm whereby said presser 70 foot will be released during the feeding operation, substantially as described.

5. In a stitching machine, the combination, with a work support, a needle jaw and an awl jaw, of a presser foot lever, a presser 75 foot mounted thereon, an arm arranged to engage said lever and having a series of ratchet teeth, a trip lever having a tooth to engage said teeth and permit said arm to move automatically in one direction, but 80 locking it against movement in the other direction, an actuating means for said awl jaw, and means adjustably mounted in said actuating means and arranged to engage and trip said trip lever at a predetermined point, 85 substantially as described.

6. In a stitching machine, the combination, with a work support and a needle jaw and an awl jaw, of a pivoted lever, a presser foot carried thereby, a spring-pressed arm 90 arranged to engage said lever having a series of ratchet teeth, a trip lever having a tooth to engage said ratchet teeth, a secondary lever arranged to engage said presser foot lever and lock the presser foot in engagement with the material, and said needle jaw having means for moving said secondary lever out of engagement with said presser 95 foot lever.

7. In a stitching machine, the combination, with a work support, an awl jaw and a needle jaw, of a pivoted lever, a presser foot carried thereby, an arm having ratchet teeth and arranged to engage said presser foot lever, means for adjusting said arm to accommodate said presser foot to the thickness of the material, a secondary lever arranged to engage said presser foot lever and lock it in its working position, said secondary lever having a part in the path of said 100 needle jaw to be actuated thereby to release said presser foot lever.

8. In a stitching machine, the combination, with a work support, a needle jaw and an awl jaw, of a pivoted lever, a presser foot mounted thereon, a spring-pressed arm arranged to hold said presser foot toward said work plate with a yielding pressure, said arm having a series of ratchet teeth, a trip lever having a tooth to engage said 115 teeth, said ratchet arm slipping automatically over said tooth to increase the pressure of said foot on said plate, but being locked normally by said tooth against movement in the other direction, a rotating post having a part to engage and actuate said awl jaw and means carried by said post to engage and operate said trip lever.

9. In a stitching machine, the combination, with a work support a needle jaw and

- an awl jaw, of a pivoted lever, a presser foot mounted thereon, a spring pressed arm arranged to hold said presser foot toward said work plate with a yielding pressure, a 5 trip lever having a ratchet connection with said arm and normally locking it against movement in one direction, a secondary lever arranged to lock said presser foot lever in its working position, said secondary 10 lever being in the path of said needle jaw to be actuated thereby, and an awl jaw operating means having a part to actuate said trip lever, substantially as described.
10. In a stitching machine, the combination, with a work support and a needle jaw, of a presser foot lever, a presser foot mounted thereon, a mechanism arranged to lock said presser foot lever but permit it to accommodate itself to the varying thickness 15 of the material, and means actuated by said needle jaw for releasing said presser foot lever at a predetermined point said means including a secondary lever disposed in the path of said jaw.
- 25 11. The combination, with a work support, a needle jaw and an awl jaw, of a presser foot lever, a presser foot carried thereby, a spring-pressed arm having a series of teeth, and a part to engage said presser 30 foot lever, a trip lever having a tooth to engage said ratchet teeth and normally lock said arm, means including a rotating post
- for actuating said awl jaw, and means carried by said actuating means for moving said trip lever to release said arm, substantially as described. 35
12. In a stitching machine, a needle jaw in combination with a presser foot mechanism comprising a presser foot lever and means arranged to engage said lever to raise the same and depress the presser foot, a trip lever having a part to contact with said engaging means, and means actuated by the movement of the needle jaw for releasing said presser foot lever. 40
13. In a stitching machine a needle jaw in combination with a presser foot mechanism comprising a presser foot lever and presser foot carried thereby, adjustable means engaging said lever and permitting it to accommodate itself to the thickness of the material, a secondary lever arranged to engage said presser foot lever and lock it in its working position, said secondary lever being actuated by the movement of the needle 45 jaw. 50

In witness whereof, we have hereunto set our hands this 24th day of April 1909.
